UNITED STATES PATENT OFFICE

WILLIAM NELSON PARKES, OF BROOKLYN, NEW YORK, ASSIGNOR TO THE SINGER MANUFACTURING COMPANY, OF ELIZABETH, NEW JERSEY, A CORPORATION OF NEW JERSEY

GUARD FOR SEWING-MACHINE LOOP TAKERS

Application filed August 11, 1927. Serial No. 212,173.

This invention relates to improvements in sewing machines of the type employing a loop-taker to cast needle-thread loops around a mass of under-thread in the formation of lock-stitches.

During the operation of a threaded sewing machine of this type in the absence of work, commonly termed "chaining off," the chain of thread thus formed is liable to sag into the path of movement of the loop-taker beak and is therefore likely to become jammed in the loop-taker raceway for the bobbin-carrier.

The present invention has for its primary object to provide means for preventing the thread-chain from being fouled by the loop-taker. A further object of this invention is to provide improved means external to the loop-taker for insuring a rapid spreading of the needle-thread loop toward the throat of the loop-taker beak or loop-seizing hook at the beginning of the movement of said beak to cast the needle-thread loop about a mass of under-thread.

The present improvement has been embodied in a sewing machine having a loop-taker of the vertical-axis type, in which the loop-taker beak has a horizontal path of motion directly beneath the cloth-plate of the machine. In its preferred embodiment, the improvement comprises a horizontally disposed, segmental guard-finger overlying that portion of the loop-taker beak path first traversed after seizure of the needle-thread loop by said beak. The guard-finger is adjustably secured upon the machine frame below the cloth-plate and its shank portion is provided with a needle clearance notch, one wall of said notch constituting a stationary abutment for hastening the expansion of the loop by detaining the junction of its limbs while the loop is being distended by the loop-taker beak.

In the accompanying drawings, Fig. 1 is a substantially central, longitudinal section, partly in elevation, of a portion of a sewing machine cloth-plate and its attached loop-taker mechanism bracket and showing the usual reciprocatory needle at substantially the lower end of its stroke. Fig. 2 is a top

plan view of the same portion of the cloth-plate, but omitting the throat-plate, slide-plates and the feed-dog. Fig. 3 is a detail perspective view of the guard-finger. Certain features of this loop-taker mechanism are shown more in detail in my application Serial No. 212,172 filed simultaneously herewith.

Referring to the drawings, the present improvement is shown as embodied in a sewing machine having the usual bed or cloth-plate 1, the throat-plate 2 and the slide-plates 3 and 4 at the opposite sides of the throat-plate. Operating through suitable openings in the throat-plate are the feed-dog 5 and the reciprocatory needle 6.

Suitably secured to the underside of the bed-plate 1 is the loop-taker bracket 7 sustaining the loop-taker mechanism in its assembled form as a detachable unit. Journaled in said bracket 7 is the forward end of the loop-taker actuating shaft 8, which rotates once for each complete reciprocation of the needle. The actuating mechanism for the needle and the shaft 8 may comprise any usual, properly timed construction, such as is illustrated, for instance, in the United States patent to J. C. Ringe, No. 1,484,191, dated Feb. 19, 1924. Also journaled in the bracket 7 is the vertically disposed loop-taker shaft 9 geared to the shaft 8 to derive two rotations for each rotation of said shaft 8. Secured upon the upper end of the shaft 9 is a horizontally rotating loop-taker 10 having a loop-seizing beak 11. It will be observed from Fig. 1 of the drawings that the point of the beak 11 is located at the upper rim of the loop-taker body and that it is directly below the throat-plate 2 and the slide-plate 4. Journaled in a suitable raceway in the loop-taker 10 is a carrier 12 for a bobbin 13, the bobbin-carrier being restrained against rotation with the loop-taker in any usual or well known manner.

The present invention comprehends means functioning primarily to prevent the thread chain, formed when "chaining-off," from sagging into the path of rotation of the loop-taker beak. To this end there is

provided a segmental guard-finger 14, out of contact with but directly overlying that portion of the loop-taker beak path first traversed after seizure of the needle-thread 5 loop by said beak. The guard-finger extends laterally from its shank 15, adjustably secured upon a portion of the bed-plate 1 below the slide-plate 3, the securing means comprising a screw 16 passing 10 through an elongated slot 17 formed in said shaft 15.

At the point of juncture of the guard-finger 14 with its shank 15, the latter is formed with a notch 18 to provide clearance for the needle 6, the rearward wall 19 of said notch constituting an abutment for the loop of needle-thread seized by the loop-taker. As the lower surface of the guard-finger is barely out of contact with the loop-taker beak and as the abutment wall 19 is opposed to the direction of movement of said loop-taker beak when seizing a loop of needle-thread, it is apparent that said wall 19 functions to cause the needle-thread 25 loop to slide along the loop-taker beak and to be rapidly spread by the inclined edge 20 of said beak. The projection 21 forming the forward wall of the notch 18 is partly cut away and is beveled upwardly 30 to guide the needle-thread loop as it is drawn up after being cast about the bobbin-carrier.

Having thus set forth the nature of this invention, what I claim herein is:

35 1. In a sewing machine, a cloth-plate, a reciprocatory needle, a vertical-axis loop-taker below said cloth-plate having a loop-seizing beak traversing a horizontal path to cast needle-thread loops about a lower-thread mass, and a stationary guard-member disposed between the loop-taker and the cloth-plate overlying that portion of the loop-taker beak path first traversed by said beak after engagement of the needle-thread 40 loop to thereby prevent sagging of the thread-chain into said loop-taker beak path.

50 2. In a sewing machine, a cloth-plate, a reciprocatory needle, a vertical-axis loop-taker below said cloth-plate having a loop-seizing beak traversing a horizontal path to cast needle-thread loops about a lower-thread mass, and a fixed segmental guard finger disposed between the loop-taker and the cloth-plate, said guard-finger overlying 55 a portion of the loop-taker beak path to prevent sagging of the thread-chain into said path.

60 3. In a sewing machine, a cloth-plate, a reciprocatory needle, a vertical-axis loop-taker below said cloth-plate having a loop-seizing beak traversing a horizontal path of movement to cast needle-thread loops about a lower-thread mass, and a fixed segmental guard-finger disposed between the loop-taker and the cloth-plate to overlie a por-

tion of the loop-taker beak path, said guard-finger being provided with a needle-thread loop abutment wall directly rearward of the needle.

4. In a sewing machine, a cloth-plate, a reciprocatory needle, a vertical axis loop-taker below said cloth-plate having a loop-seizing beak traversing a horizontal path of movement to cast needle-thread loops about a lower-thread mass, and a fixed segmental guard-finger disposed between the loop-taker and the cloth-plate to overlie a portion of the loop-taker beak path, said guard-finger being provided with a needle-clearance notch, the rearward wall of said notch constituting a needle-thread loop abutment, and the portion of the guard-finger in front of the notch being beveled upwardly toward the cloth-plate to guide the discharged needle-thread loop.

In testimony whereof I have signed my name to this specification.

WILLIAM NELSON PARKES.
